UNITED STATES PATENT OFFICE.

CHARLES F. MATTINGLY, OF MAPLEWOOD, AND CECIL F. MONTGOMERY, OF ST. LOUIS, MISSOURI, ASSIGNEES TO MATTINGLY AUTOMATIC VALVE CO., OF ST. LOUIS, MISSOURI, A CORPORATION OF MISSOURI.

NONRETURN VALVE.

Application filed May 29, 1922. Serial No. 564,371.

To all whom it may concern:

Be it known that CHARLES F. MATTINGLY and CECIL F. MONTGOMERY, citizens of the United States, residing at Maplewood, in the 5 county of St. Louis and State of Missouri, and St. Louis, State of Missouri, respectively, have invented certain new and useful Improvements in Nonreturn Valves, of which the following is a specification, reference being had to the accompanying drawings.

This invention relates to certain improvements in non-return valves and has relation more particularly to a device of this general 15 character of an automatic type and it is an object of the invention to provide a novel and improved device of this general character which is particularly designed and adapted for use for shutting off the flow of 20 gas from the tank of an oxy-acetylene apparatus in case the hose is bursted, burned into or ruptured from any cause and which also operates to prevent fire from going back into the tank in the event of a flash 25 back or back fire of the torch.

The invention consists in the details of construction and in the combination and arrangement of the several parts of our improved non-return valve whereby certain important advantages are attained and the device rendered simpler, less expensive and otherwise more convenient and advantageous for use, as will be hereinafter more fully set forth.

35 The novel features of our invention will hereinafter be definitely claimed.

In order that our invention may be the better understood, we will now proceed to describe the same with reference to the accompanying drawings, wherein:

Figure 1 is a view partly in section and partly in elevation illustrating a non-return valve constructed in accordance with an embodiment of our invention;

45 Figure 2 is a view partly in section and partly in top plan of the bushing and valve associated therewith; and

50 Figure 3 is a view in elevation of the outer end of the structure illustrated in Figure 2.

As disclosed in the accompanying drawings, C denotes a casing herein shown as substantially L-shaped in form and which has one end portion 1 internally threaded

so that the casing may be suitably connected or coupled to a tank containing oxy-acetylene gas or other source of fluid under pressure. The opposite end portion 2 of the casing C is exteriorly threaded to facilitate the connection or coupling therewith of the hose or tube H. The portion 1 of the casing C is provided with an internal main valve seat 3 with which co-acts a main valve 4. The valve 4 is secured to an end portion of a valve stem 5 which has its inner end portion or its end portion remote from the valve 4 threaded into or otherwise engaged with a fulcrum piece or block 6. The block 6 is pivotally engaged as at 7 with an end portion of a link 8. The center portion of the link 8 is pivotally engaged as at 9 with a pin or a member a which intersects the body of the casing C.

The wall of the casing C, remote from the end portion 1 and at a point thereabove is provided with an opening 10 in which is threaded a bushing 11, the bore of said bushing being preferably cylindrical. Freely disposed through the bore 12 of the bushing 11 is an elongated stem 13 angular 75 in cross section and preferably square. The inner end portion of the stem 13 is provided with a valve 14 which co-acts with the valve seat 15 arranged at the inner end of the bore 12. The stem 13 is provided with an extension disposed in advance of the valve 14, said extension being bifurcated with the kerf 16 thereof bridged by the pin 17, said pin being spaced a desired distance from the valve 14. A second end portion of the link 8 extends through the kerf 16 between the pin 17 and the valve 14 so that the valves 4 and 14 will be caused to move in unison but in reverse direction.

The bore 12 of the bushing 11 affords 95 communication between the atmosphere and the bore of the casing C and the stem 13 is of a length to extend exteriorly of the casing C and beyond the bushing 11 and the exterior end portion of the stem 13 is provided 100 with a ring 18 or the like to provide means whereby the valves 4 and 14 may be manually operated when required. The end portion 2 of the casing C is provided with an internal valve seat 19 with which co-acts a ball valve 20, said ball valve moving away from its seat upon the pressure of the fluid passing through the casing to permit free 105

and unobstructed flow of such fluid through the casing C. The ball valve 20 drops to its seat 19 upon back pressure or when the pressure within the casing C inwardly of the 5 valve seat 19 is materially reduced. The ball valve 20 is held in place by means of the rivet or pin 21 which intersects the end portion 2 of the casing C to force no undue obstruction or hindrance of the flow through 10 said casing.

When the valve 4 is in closed position or resting against its seat 3, the valve 14 is in open position or off its seat 15. When it is desired to use the torch or to permit a 15 flow through the casing C the stem 13 is pulled outwardly, which action seats the valve 14 and moves the valve 4 into open position. As the pressure builds up in the 20 hose H the pressure also builds up within the body portion of the casing C, which pressure serves to hold the valve 4 in open position and the valve 14 tightly against its seat.

As the area around the valve 4 is smaller 25 than the cross sectional area of the bore or passageway within the body of the casing C or the corresponding area of the hose or pipe H it will be readily seen that were it not for the pressure acting against the valve 14, 30 the velocity of the pressure passing around the valve 4, would quickly force said valve 4 to its seat and stop the flow. However, the area around the valve 4 is larger than the cross sectional area of the nozzle or tip 35 of the torch being operated and therefore the torch may be employed without creating any reduction of pressure in the hose or pipe H and consequently the valve 4 will not move into closed position and the ball 40 valve 19 will remain off its seat 20 while the torch is being used. When the torch is shut off the pressure will equalize on each side of the ball valve 19 whereupon said 45 valve 19 will fall to its seat 20 by gravity. However, the main purpose of the ball valve 19 is to prevent fire from running back into the tank and especially in case of flash 50 back or back fire of the torch.

Should the hose become burned in two or 55 ruptured from any cause as is often the case, the pressure which has been built up in the hose or pipe H and within the casing C will suddenly lessen or relieve the pressure on the valve 14 which was holding it to its seat 15 and, as the area around the valve 4 is not large enough to allow pressure enough to pass around it to supply the opening caused by the bursted hose or pipe H, the velocity of 60 the gas or fluid passing around said valve 4 and the excessive force of the gas or fluid remaining within the tank or other source of supply will force the valve 4 to its seat and thereby close the communication between the tank and hose.

In case of flash back or back firing, which must begin in the torch, as this is the only place where the two gases come in contact with each other, the instant the flash back or back fire begins it will create a pressure 70 in the hose or pipe H which will overcome the pressure of the gas which is passing around the ball valve 19 and as soon as this pressure equalizes the ball valve 19 will fall to its seat and thus prevent the passage of 75 the fire back through the casing C.

From the foregoing description it is thought to be obvious that a non-return valve constructed in accordance with our invention is particularly well adapted for use 80 by reason of the convenience and facility with which it may be assembled and operated, and it will also be obvious that our invention is susceptible of some change and modification without departing from the 85 principles and spirit thereof and for this reason we do not wish to be understood as limiting ourselves to the precise arrangement and formation of the several parts herein shown in carrying out our invention in 90 practice except as hereinafter claimed.

We claim:

1. A valve of the class described comprising a casing, one end of which being adapted for communication with a source of fluid under pressure, the bore of said casing inwardly of its opposite ends being provided with internal valve seats, the portion of the bore of the casing inwardly of the seat in the induction end of the casing constituting a pressure chamber, a gravity seating valve co-acting with the second internal valve seat, the pressure within the casing serving to lift said valve from its seat, a wall of the casing being provided with a port in communication with the pressure chamber of the casing and with the atmosphere, a valve co-acting with the port, a valve co-acting with the internal valve seat in the induction end of the casing, and means within the casing 100 for connecting said last named valves for movement in unison but in reverse directions, one of the valves being in open position 105 when the other is in closed position.

2. A valve of the class described comprising a casing, one end of which being adapted for communication with a source of fluid under pressure, the bore of said casing inwardly of its opposite ends being provided with internal valve seats, the portion of the bore of the casing inwardly of the seat in the induction end of the casing constituting a pressure chamber, a gravity seating valve co-acting with the second internal valve seat, the pressure within the casing serving to lift said valve from its seat, a wall of the casing being provided with a port in communication with the pressure chamber of the casing and with the atmosphere, a valve co-acting with the port, a valve co-acting 115

with the internal valve seat in the induction end of the casing, means within the casing for connecting said last named valves for movement in unison but in reverse directions, one of the valves being in open position when the other is in closed position, and the stem associated with the valve co-acting with the port and extending through the port exteriorly of the casing, said stem 10 providing means for manually moving the last named valves.

3. A valve of the class described comprising a casing adapted for communication with a source of fluid under pressure, the 15 bore of said casing being provided with an internal valve seat, the portion of the bore at the induction side of the valve seat constituting a pressure chamber, a wall of the casing being provided with a port in communication with the bore of the casing outwardly of the internal valve seat, a valve coacting with the internal valve seat, a valve coacting with the port, a member positioned within the casing and extending diametrically thereacross from one wall of the casing to another, a link arranged within the casing and pivotally supported between its ends by the member, the opposite end portions of the link being operatively engaged 20 with the valves to cause the valves to move in unison but in reverse directions, the connection between the link and one of the valves comprising a bifurcated extension carried by said valve, a pin bridging the 25 kerf of the bifurcation and spaced from the valve, an end portion of the link extending between the pin of the extension and the valve.

4. A valve of the class described comprising a casing, one end of which being adapted for communication with a source of fluid 30 under pressure, the bore of said casing inwardly of its opposite ends being provided with internal valve seats, the portion of the bore of the casing inwardly of the seat in the induction end of the casing constituting a pressure chamber, a gravity seating 35 valve co-acting with the second internal valve seat, the pressure within the casing serving to lift said valve from its seat, a wall of the casing being provided with a 40 port in communication with the pressure chamber of the casing and with the atmosphere, a valve co-acting with the port, a valve co-acting with the internal valve seat in the induction end of the casing, means 45 within the casing for connecting said last named valves for movement in unison but in reverse directions, one of the valves being in open position when the other is in closed position, and means for limiting the 50

movement of the gravity valve away from its seat.

5. A valve of the class described comprising a casing adapted for communication with a source of fluid under pressure, the bore of said casing being provided with an 55 internal valve seat, the portion of the bore at the induction side of the valve seat constituting a pressure chamber, a wall of the casing being provided with a port in communication with the bore of the casing outwardly of the internal valve seat, a valve coacting with the internal valve seat, a valve coacting with the port, a member positioned 60 within the casing and extending diametrically thereacross from one wall of the casing to another, a link arranged within the casing and pivotally supported between its ends by the member, the opposite end portions of the link being operatively engaged 65 with the valves to cause the valves to move in unison but in reverse directions, the connection between the link and one of the valves comprising a bifurcated extension carried by said valve, a pin bridging the 70 kerf of the bifurcation and spaced from the valve, an end portion of the link extending between the pin of the extension and the valve.

6. A valve of the class described comprising a casing adapted for communication with a source of fluid under pressure, the bore of said casing being provided with an internal valve seat, the portion of the bore at the induction side of the valve seat constituting a pressure chamber, a wall of the 75 casing being provided with a port in communication with the bore of the casing outwardly of the internal valve seat, a valve coacting with the internal valve seat, a valve coacting with the port, a member positioned 80 within the casing and extending diametrically thereacross from one wall of the casing to another, a link arranged within the casing and pivotally supported between its 85 ends by the member, the opposite end portions of the link being operatively engaged with the valves to cause the valves to move in unison but in reverse directions, and means for manually moving the valves.

In testimony whereof they hereunto affix their signatures.

CHARLES F. MATTINGLY.
CECIL F. MONTGOMERY.
